US0D1004419S

(12) **United States Design Patent** (10) **Patent No.:** **US D1,004,419 S**
(45) **Date of Patent:** **** Nov. 14, 2023**

(54) **PACKAGING**

(71) Applicant: **Philip Morris Products S.A.,**
Neuchâtel (CH)

(72) Inventor: **Hiromi Suzuki**, San Francisco, CA
(US)

(73) Assignee: **Philip Morris Products S.A.,**
Neuchâtel (CH)

(**) Term: **15 Years**

(21) Appl. No.: **29/759,839**

(22) Filed: **Nov. 25, 2020**

(30) **Foreign Application Priority Data**

Jun. 12, 2020 (EM) 007999925

(51) **LOC (14) Cl.** **09-03**

CLAIM

The ornamental design for a packaging, as shown and described.

DESCRIPTION

FIG. 1 is a front, top, and left side perspective view of a packaging, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines depict portions of the packaging that form no part of the claimed design.

1 Claim, 7 Drawing Sheets
